UNITED STATES PATENT OFFICE.

MEYER L. ROBBINS, OF NEW YORK, N. Y.

CIGAR-CUTTER.

1,086,463.

Specification of Letters Patent. Patented Feb. 10, 1914.

Application filed January 6, 1913. Serial No. 740,331.

To all whom it may concern:

Be it known that I, MEYER L. ROBBINS, a citizen of the United States, and a resident of New York, borough of Manhattan, in the county of New York and State of New York, have made and invented certain new and useful Improvements in Cigar-Cutters, of which the following is a specification.

My invention relates to cigar cutters of the kind or type adapted to be carried in the pocket of the user and designed to cut the end or tip from a cigar preparatory to smoking the same, and the object thereof is to provide an improved cigar cutter of the type above referred to which will be neat and attractive in appearance, which will be of small size, which will have no objectionable projecting portions when closed and in the condition in which it is carried in the pocket, and which may be readily and cheaply manufactured and will be effective for the purpose for which it is designed.

With the above and other objects of invention in view, my invention consists in the improved cigar cutter illustrated in the accompanying drawing and hereinafter described and claimed, and in such variations and modifications thereof as will be obvious to those skilled in the art to which my invention relates.

In the drawing: Figure 1 is a view showing my improved cigar cutter in perspective and in its open condition; Fig. 2 is a view showing the same in its closed condition with one side thereof removed to show internal construction; Fig. 3 is a view showing a section upon a longitudinal plane indicated by the line 3—3, Fig. 2; Fig. 4 is a view similar to Fig. 2 but showing the device in its open condition preparatory to cutting the tip from a cigar; Fig. 5 is a view similar to Fig. 3, but taken upon a plane indicated by the line 5—5, Fig. 4; Fig. 6 is a view showing a section upon a transverse plane indicated by the line 6—6, Fig. 4; and Fig. 7 is a view showing a detail of a catch which forms a part of the cigar cutter.

Referring to the drawings wherein the preferred embodiment of my invention is illustrated, the reference numeral 8 designates two parallel side walls spaced apart and connected with one another by means of

narrow end strips 9 to thereby form a thin hollow casing within which the operative parts of the cutter are located, and which casing obviously presents a smooth exterior surface without projections which might catch in the pocket of the user.

The side walls or plates above referred to are provided each with an opening shown at 10, and flanges 11 are preferably provided which surround these openings and extend toward one another to thereby provide a smooth opening or socket into which the end of the cigar may be placed preparatory to cutting the tip therefrom, and the form of which opening is such that the end of the cigar will not be liable to injury. The inner ends of these flanges approach close to one another, but do not meet; and the reference numeral 12 designates a reciprocating knife having a cutting edge 13 movable between the inner ends of the flanges and across the openings in the casing to thereby cut the end from a cigar as will be understood. The knife 12 is operatively connected with two reciprocating tubular members 14 adapted to move into and out of the hollow casing of the cutter; Figs. 1 and 4 showing these tubular members in their outermost position, while Figs. 2 and 3 show them in their innermost position. The knife may be connected with the tubular members in any way so as to move therewith, although I prefer to provide stiffening strips 15 extending partly or entirely around the periphery of the knife and bent over the ends thereof as shown at 16, 17, which strips are in turn secured to the tubular members as by being soldered thereto. This construction permits the use of an exceedingly thin knife as the strips extend along the periphery thereof and help to support the same, a thin knife being especially advantageous for the reason that its cutting edge is less likely to become dull than the cutting edge of a thicker knife.

The tubular members 14 are connected with one another at their outer ends as by means of a yoke 18, and the reference numeral 19 designates guides located within the hollow casing of the cutter and secured in place in any way, which guides extend into the tubular members 14 and thereby

guide the inner ends of the said members and the knife carried by them as said members and the knife are operated.

Within the tubular members 14 are located 5 springs 20, one end of each of which abuts against the end of a guide 19 and the other end against the yoke 18, as will be understood from Fig. 4, which springs serve to force the guide members and the knife outward and into the position shown in Figs. 1 and 4, this being the position the parts assume preparatory to cutting the tip from a cigar.

The reference numeral 21 designates a 15 latch located within the casing of the cutter and secured in place in any way, the outer or free end of which is provided with a catch 22 adapted to engage a ledge 23 of the yoke 18 as shown in Fig. 3 of the drawing. The 20 catch 22 may be disengaged from the ledge 23 by means of a button 24 adapted to be pressed by the finger, whereupon the tubular members and yoke are moved by the springs 20 from the closed position shown in Fig. 2 25 into the open position shown in Figs. 1 and 4.

The cigar cutter having been permitted to open as above explained, the end of a cigar is placed within the opening 10 and the yoke 18 pressed toward the casing, which obviously causes the knife to move across the opening and thus cuts the end from a cigar. As the yoke is moved against the casing, the ledge 23 passes over the hook or catch 22 of the latch 21 and the latch holds the parts in 30 the closed position shown in Fig. 3 until the cigar cutter is to be again used. The latch 21 is provided with a projecting stop 25 with which the knife engages at the end of the outward movement thereof, as shown in Fig. 40 5, to thereby limit the outward movement thereof and prevent the knife from leaving the casing. It will be thus seen that when the cutter is closed it is in the form of an oblong rectangular case having no projecting parts to catch in the pocket of the user, and that it is exceedingly compact, and occupies but little space. In addition, the knife is located entirely within the external casing and the cutting edge thereof is in such 45 50 a position that it is entirely protected from contact with external objects when the cutter is closed and in the condition in which it is carried in the pocket.

Having thus described and explained my 55 invention, I claim and desire to secure by Letters Patent:

1. A cigar cutter comprising a hollow casing having two parallel side walls each having an opening and which openings register 60 with one another; two guides located within said casing; two reciprocating tubular members the inner ends of which engage and are guided by said guides, and which members extend without the casing; a yoke with which the outer ends of said tubular members are connected; a spring located within each of said tubular members; and a knife located within said casing with which 65 said tubular members are operatively connected, and which knife is adapted to move

bers are connected; a spring located within each of said tubular members; and a knife located within said casing and carried by said tubular members, and which knife is adapted to move across the opening aforesaid in said casing; a latch located within said casing and adapted to engage said yoke to thereby hold said tubular members in their innermost position; and means for operating said latch to release said yoke.

70

2. A cigar cutter comprising a hollow casing having two parallel side walls each having an opening; an inwardly projecting flange surrounding each of said openings and which flanges are formed integrally with said side walls; two guides located within said casing; two reciprocating tubular members the inner ends of which engage and are guided by said guides, and which members extend without the casing and are connected with one another at their outer ends; a spring located within each of said tubular members; and a knife located within said casing and with which said tubular members are operatively connected, and which knife is adapted to move between the inner ends of said flanges and across the opening aforesaid in said casing.

80

3. A cigar cutter comprising a hollow casing having two parallel side walls each having an opening; an inwardly projecting flange surrounding each of said openings and which flanges are formed integrally with said side walls; two guides located within said casing; two reciprocating tubular members the inner ends of which engage and are guided by said guides, and which members extend without the casing and are connected with one another at their outer ends; a spring located within each of said tubular members; and a knife located within said casing and with which said tubular members are operatively connected, and which knife is adapted to move between the inner ends of said flanges and across the opening aforesaid in said casing; and a latch located within said casing and adapted to hold said tubular members in their innermost position.

90

4. A cigar cutter comprising a hollow casing having two parallel side walls each having an opening; an inwardly projecting flange surrounding each of said openings and which flanges are formed integrally with said side walls; two guides located within said casing; two reciprocating tubular members the inner ends of which engage and are guided by said guides, and which members extend without the casing; a yoke with which the outer ends of said tubular members are connected; a spring located within each of said tubular members; and a knife located within said casing with which said tubular members are operatively connected, and which knife is adapted to move
